US0D1112496S

(12) United States Design Patent (10) Patent No.: US D1,112,496 S
(45) Date of Patent:  *Feb. 10, 2026

(54) BANK OF GAMING MACHINES INCLUDING
LIGHT BAR

(71) Applicant: Aristocrat Technologies, Inc., Las Vegas, NV (US)

(72) Inventors: Rena Schoonmaker, Las Vegas, NV (US); Timothy Seckel, Streamwood, IL (US); James McNierney, Las Vegas, NV (US); Bruce Urban, Las Vegas, NV (US)

(73) Assignee: Aristocrat Technologies, Inc., Las Vegas, NV (US)

(*) Notice: This patent is subject to a terminal disclaimer.

() Term: 15 Years

(21) Appl. No.: 29/917,881

(22) Filed: Nov. 22, 2023
